DESIGN FOR A BABY'S BOTTLE HOLDER OR THE LIKE

Michael Graboi, New York, N. Y.

Application January 28, 1948, Serial No. 144,115

Term of patent 14 years

(Cl. D83—8)

To all whom it may concern:

Be it known that I, Michael Graboi, a citizen of the United States, residing at New York, county and State of New York, have invented a new, original, and ornamental Design for a Baby's Bottle Holder or the like, of which the following is a specification, reference being had to the accompanying drawing forming a part thereof, wherein:

Fig. 1 is a side elevational view of a bottle holder showing my design;

Fig. 2 is a front elevational view of the bottle holder; and

Fig. 3 is a top plan view of the bottle holder.

The dominant features of my invention are shown in full lines.

I claim:

The ornamental design for a baby's bottle holder or the like, substantially as shown and described.

MICHAEL GRABOI.
